Attorney

UNITED STATES PATENT OFFICE.

CHARLES L. BETTS, OF BROOKLYN, ASSIGNOR TO THE R. E. DIETZ COMPANY, OF NEW YORK, AND THE STEAM GAUGE AND LANTERN COMPANY, OF SYRACUSE, NEW YORK.

TUBULAR LANTERN AND LAMP.

SPECIFICATION forming part of Letters Patent No. 451,551, dated May 5, 1891.

Application filed January 28, 1891. Serial No. 379,362. (No model.)

To all whom it may concern:

Be it known that I, CHARLES L. BETTS, of Brooklyn, county of Kings, and State of New York, have invented certain new and useful 5 Improvements in Tubular Lanterns and Lamps, of which the following is a full, clear, and exact description, reference being had to the accompanying drawings, and to the letters of reference marked thereon.

10 My invention relates to that class of lanterns and lamps wherein the air for support of combustion is conducted from the region of the outlet for products of combustion down to the under side of the burner-cone through tubes, and commonly known as "tubular" 15 lanterns and lamps.

While I herein show my improvements as applied in connection with a ship or signal lantern, it should be understood that they 20 may be applied in other forms of tubular lanterns and lamps wherein their use may be found convenient and advantageous.

Among the objects of my invention are the provision of a simple, cheap, and substantial 25 base for the structure, which base shall, together with the removable oil-pot, the perforated extension thereof, and the air-conducting tubes, form independent channels or passage-ways for heated air passing to the under side of the burner-cone and for cool air 30 passing to the exterior of the flame, the provision of simple and efficient means for locking the oil-pot in place and closing the bottom of the chamber which receives the oil-pot, and the provision of a cheap and reliable means for locking the globe upon its 35 seat, but permitting its removal when desired. To accomplish these objects and to secure other and further advantages in the matters 40 of construction, operation, and use, my improvements involve new and useful arrangements or combinations of parts and peculiarities of construction, as will be herein first fully described, and then pointed out in the 45 claims.

In the drawings, Figure 1 is a vertical view, partly in section and partly in elevation, showing an illuminating apparatus in the form of a ship or signal lantern having my

improvements applied thereto and ready for use. Fig. 2 is a horizontal section on a plane through line $\alpha\alpha$ of Fig. 1, showing the manner of mounting and locking the ring which holds the globe in place. Fig. 3 is an elevation of the oil-pot with its perforated extension as it appears when detached from the base of the lamp. Fig. 4 is a partial view of a section on a plane through line yy of Fig. 1, showing the manner of locking the oil-pot in place for use.

In all the figures like letters of reference wherever they occur indicate corresponding parts.

A is the globe; B B, the vertical air-conducting tubes; C, the oil-pot; D, the burner-cone; E, the outer wall of the base of the lantern structure, and F the top or dome.

A is the globe; B B, the vertical air-conducting tubes; C, the oil-pot; D, the burner-cone; E, the outer wall of the base of the lantern structure, and F the top or dome.

In the form shown air for the support of combustion enters the tubes from a perforated bell or funnel G, located under the top or dome F; but the form and arrangement of the inlet are not material. From the inlet air passes down the tubes and reaches the under side of the burner-cone through a channel or passage-way closed against admission of other air, and the products of combustion escape at the opening beneath the dome.

Within the outer wall E of the base and mounted on the same bottom E' is erected another wall or partition H, leaving between the two a space I, into which fresh air enters from the exterior through perforations a a. Upon the wall or partition H is an inwardly-projecting flange H', against which the top of the extension of the oil-pot bears when the oil-pot is in place. The wall of the oil-pot is extended and perforated, as at b b, the extension being covered by a top or plate K, over which the burner-cone rests, an air-passage being thus provided over the top of the oil-pot. The lower portions of the tubes B pass through the outer wall E, through the space or passage I, and through the partition H, delivering their contents into a chamber L between partition H and the oil-pot, the latter being of shorter diameter than the said partition for the purpose of affording the desired chamber. From this chamber air passes

through the perforations *b* and up to the under side of the burner-cone.

To close the bottom of chamber *L*, so that no passing current of exterior air or wind will 5 disturb the contents of the chamber, the oil-pot is supplied with a flange *M*, which extends well beyond the margin of the opening in the bottom of the structure through which the oil-pot is inserted, and this flange is crowded 10 up to a tight joint with the bottom by the means adopted for locking and holding the oil-pot in place, which will be hereinafter explained.

The globe rests upon the ring or wall *E*, 15 and is there secured when the lamp is in use. Air from the exterior enters through perforations *a* and passes up into the globe through the open top of chamber *L*. The perforations *a* are made small or fine, so as to prevent the 20 admission of violent currents of air, thus maintaining a steady light, at the same time keeping the globe cool and supplying the requisite amount of air for the interior of the flame-chamber, as in other forms of tubular 25 lanterns.

The oil-pot is detachable bodily from the base of the structure, so that it may be filled and cleaned, and the opening then left in the base is amply large to afford access to the interior of the globe for cleaning, the base being 30 strong and well braced upon the tubes by reason of the double connections with their lower extremities.

Upon the lower portion of the oil-pot are 35 projecting pins *c c* entering corresponding slots in the inwardly-projecting margin of the base or bottom *E'* and riding upon the upturned portions or edges *d d* between said slots, the said upturned portions or edges being 40 slightly inclined.

By turning the oil-pot after it has been adjusted to place the flange *M* can be crowded to its seat with any desired pressure, and the pot locked in place against any accidental 45 disarrangement or disturbance.

For convenience in turning and handling, the oil-pot is supplied with a cross-handle *N*, applied on its base.

The globe is held to its seat by a ring *O*, 50 which bears upon the upper margin of the globe and slides up and down closely inside the wall *P* or the upper portion of the lantern to economize space at this portion. Projecting pins *e e* extend from ring *O* out through 55 angular slots *f* in the wall *P*. These slots and the pins therein are covered by exterior cap-plates *g*, through one of which projects a lock- ing-spring *h*. When the ring *O* is down upon

the globe and turned sufficiently, the spring prevents any accidental movement, and may 60 be released whenever required to remove the globe. When the ring *O* is raised, it may be held in elevated position by turning the pins in the upper horizontal branches of the slots provided for them. This arrangement is compact, avoids the necessity of complicated fittings for the purpose of holding and releasing the globe, and leaves the lantern unencumbered at the top.

The wire guard and the means of suspending the lantern may be varied as occasion may require. The wick-raiser is by preference operated by a shaft projecting down through the oil-pot, as shown, so that the flame may be regulated without disturbing 75 the oil-pot.

Having now fully described my invention, what I claim as new herein, and desire to secure by Letters Patent, is—

1. In a tubular lantern, the combination of 80 an outer perforated base-wall, an inner partition, air-conducting tubes passing through both said wall and partition, and a removable oil-pot having an air-passage formed on its top, these parts being arranged to afford 85 passages for air from the tubes and from the exterior of the lantern, substantially in the manner and for the purposes set forth.

2. In a tubular lantern, the combination, 90 with the removable oil-pot, the base or bottom of the lantern, and the air-chamber formed around the oil-pot, of a flange applied to said oil-pot and adapted to close the lower opening in said chamber, substantially in the manner shown and described.

3. In a tubular lantern, the combination, 95 with the base-piece supporting an outer and an inner wall and having an inwardly-projecting slotted and upturned flange, of the removable oil-pot provided with projecting 100 pins, substantially as and for the purposes set forth.

4. In a tubular lantern, the combination of the removable globe, a globe-holding ring fitting the upper vertical wall of the lantern 105 and provided with projecting pins passing through slots in said wall, a retaining-spring, and cap-plates covering the pins, substantially as shown and described.

In testimony that I claim the foregoing I 110 have hereunto set my hand in the presence of two witnesses.

CHARLES L. BETTS.
